UNITED STATES PATENT OFFICE

WILLIAM M. MOORE, OF PHILADELPHIA, PENNSYLVANIA

DESIGN FOR A STAND

Application filed February 28, 1929. Serial No. 30,248. Term of patent 3½ years.

To all whom it may concern:

Be it known that I, WILLIAM M. MOORE, a citizen of the United States, residing at Philadelphia, in the county of Philadelphia and State of Pennsylvania, have invented a new, original, and ornamental Design for Stand, of which the following is a specification, reference being had to the accompanying drawing, forming a part thereof.

I claim:

The ornamental design for a stand as shown.

WILLIAM M. MOORE.
